VALVE CHAMBER FOR A CONCRETE PUMP OR THE LIKE

Marvin D. Bennett, Wilmington, Calif., assignor to Royal
Industries, Inc., Gardena, Calif., a corporation of
California

Filed Feb. 11, 1965, Ser. No. 83,787

Term of patent 14 years

(Cl. D65—1)

FIG. 1.

FIG. 2.

FIG. 3.

FIG. 4.

FIG. 1 is a perspective view of a valve chamber for a concrete pump or the like showing my new design.

FIG. 2 is a left hand elevational view of the valve chamber for a concrete pump or the like as illustrated in FIG. 1.

FIG. 3 is a top plan view of the valve chamber for a concrete pump or the like of FIG. 1.

FIG. 4 is a bottom plan view of the valve chamber for a concrete pump or the like as illustrated in FIG. 1.

FIG. 5 is a front elevational view of the valve chamber for a concrete pump or the like of FIG. 1.

FIG. 6 is a back elevational view of the valve chamber for a concrete pump or the like of FIG. 1.

I claim:

The ornamental design for a valve chamber for a concrete pump or the like, as shown.
